UNITED STATES PATENT OFFICE.

JONAS NORTHROP, OF HOPEDALE, MASSACHUSETTS, ASSIGNOR TO DRAPER COMPANY, OF HOPEDALE, MASSACHUSETTS, A CORPORATION OF MAINE.

TAKE-UP-ARRESTING MECHANISM FOR LOOMS.

SPECIFICATION forming part of Letters Patent No. 729,644, dated June 2, 1903.

Application filed December 17, 1902. Serial No. 135,580. (No model.)

To all whom it may concern:

Be it known that I, JONAS NORTHROP, a subject of the King of Great Britain, and a resident of Hopedale, county of Worcester, State 5 of Massachusetts, have invented an Improvement in Take-Up-Arresting Mechanism for Looms, of which the following description, in connection with the accompanying drawings, is a specification, like characters on the 10 drawings representing like parts.

This invention relates to looms; and it has for its object the production of novel means for arresting the operation of the take-up mechanism upon a change in the normal running condition of the loom.

In accordance with my invention I have made provision for arresting take-up upon filling failure or upon filling replenishment in an automatic loom and upon the occurrence of a warp fault, the arrest of take-up being accompanied by let-back when filling replenishment is effected.

The various novel features of my invention will be described hereinafter and particularly pointed out in the following claims.

Figure 1 is a left-hand side elevation of a portion of a loom, showing the take-up mechanism and one embodiment of my invention applied thereto. Fig. 2 is an enlarged detail, 20 in side elevation, of the take-up-actuating pawl and a portion of the pawl-carrier. Fig. 3 is a transverse section thereof on the line 3-3, Fig. 2, looking toward the left; and Fig. 4 is a detail, centrally broken out, of one 25 form of warp-stop-motion mechanism, which acts to arrest take-up upon the occurrence of a warp fault.

Referring to Fig. 1, the lay-sword A^x, having a bracket a, to which the pawl-carrier a' 40 is attached, the ratchet a³, the train of gearing between its shaft and the take-up roll T, and the controlling rock-shaft d^x, having an arm d' to engage a lug a¹⁰ on the pawl-carrier to effect disengagement of the pawl and ratchet 45 when said shaft is rocked to effect filling replenishment in an automatic loom, may be and are all substantially as in United States Patent No. 610,636, dated September 13, 1898, said rock-shaft forming a part of the mechanism for effecting the operation of filling-

replenishing mechanism if the loom be provided therewith or operating stopping means in well-known manner by or through detection of filling failure.

The shipper S, pivoted at s^x on the loom side, 55 and its notched holding-plate N are of well-known construction and operate in usual manner, release of the shipper from its holding-notch acting through familiar means to throw off the power.

In the patent referred to the actuating-pawl is rigidly mounted on the pawl-carrier; but herein I have movably mounted the pawl thereon, and the pawl-carrier has been slightly changed in consequence to properly 65 sustain the pawl.

Referring to Figs. 2 and 3, the pawl-carrier has a laterally-extended lug a⁵, provided with a down turned end a⁶ to receive a pin a⁷, the latter extending from the depending end a⁶ to the main part of the pawl-carrier. The pawl a² has a hub a⁴, through which the pin passes, so that the pawl is pivotally mounted on the pawl-carrier and normally it depends above and in position to engage the teeth of 75 the ratchet a³, as in Fig. 1 and full lines, Fig. 2. A rearwardly-extended arm a^x on the pawl-hub is pivotally connected with a link a⁸, the lower end of the latter being slotted at 22 to receive a pin 40 on an arm g⁴ of a 80 rock-shaft g^x, mounted on the lower part of the loom-frame. The said rock-shaft has a depending arm g⁶ and an upturned arm g, bent over at its upper end and provided with an inclined cam-slot g', through which extends the 85 end of the shipper S below its fulcrum s^x, the normal position of the parts being shown in Fig. 1 with the shipper in running position.

The rock-shaft g^x and its attached arms are controlled as to their movement by suitable 90 warp-stop-motion mechanism, a link g² forming a part thereof serving to at times turn the rock-shaft g^x. The warp-stop-motion mechanism may be such, for instance, as shown and described in United States Patent No. 673,825, dated May 7, 1901, the link g² herein corresponding to the link M of said patent. In Fig. 4 I have shown the stop-motion-controlling detectors d, the co-operating feelers f, as in said patent, the usual cam- 95 100

shaft C^x, and the connections intermediate the feelers and the link, arrest of a feeler by a released detector operating through such connections to move the link g² longitudinally 5 toward the back of the loom, all substantially as described in said patent. Should a warp-thread break or run out or become unduly slack, the stop-motion mechanism will operate to swing the upper end of arm g in the direction of arrow 100, Fig. 1, and the inclined edge of the slot g' will act on the shipper below its fulcrum to move its upper end out of the holding-notch in the plate N to stop the loom. Such movement of the arm g is 10 accompanied by an upward swing of the arm g⁴, moving the link a⁸ in the direction of arrow 20, Fig. 1, to turn the pawl from full-line operative position, Fig. 2, into dotted-line position out of engagement with the ratchet a³, and manifestly take-up is thereby arrested simultaneously with release of the shipper. When the latter is released, the loom may be turned over by its momentum or by the attendant after the loom has stopped 15 without effecting any movement of the take-up mechanism.

I have shown in Fig. 1 a detent-pawl a³⁰ for the ratchet a³ and a let-back pawl a³², both of well-known construction, the former having 20 a lateral pin a³¹ extended above the pawl-carrier. When the pawl-carrier is lifted by the rotation of the rock-shaft d^x, as upon filling replenishment or detection of filling failure to disengage the take-up pawl and 25 ratchet and arrest take-up, the pawl-carrier acts upon the pin a³¹ to lift the detent-pawl a³⁰ from the ratchet. This permits the pawl a³² to operate and permits let-back of the take-up; but when take-up is arrested by or 30 through the occurrence of a warp fault the pawl a² is merely disengaged from the ratchet and the let-back means does not operate, the pawl-carrier remaining quiescent. When 35 the shipper is released, the take-up is arrested upon the occurrence of a warp fault, but without let-back, and upon filling replenishment there is arrest of take-up and also let-back.

The slot and pin connection 22 40 between 40 the link a⁸ and the arm a⁴ permits the operation of the pawl-carrier a' by or through the lay-sword without causing any movement of the pawl a² relatively to the pawl-carrier.

In Fig. 1 the feeder F of filling-replenishing 45 mechanism and the transerrer f' may be of well-known construction, such, for instance, as shown in United States Patent No. 529,940. The usual filling-fork f⁵ and its slide f⁶ are indicated in Fig. 1, outward movement of 50 the slide upon detection of filling failure acting through the arm d³⁵ to rock the shaft d^x in well-known manner.

My invention is not restricted to the precise construction and arrangement herein shown 55 and described, as the same may be modified or varied in different particulars by those

skilled in the art without departing from the spirit and scope of my invention.

Having described my invention, what I claim as new, and desire to secure by Letters 70 Patent, is—

1. In a loom, take-up mechanism, including a pawl-carrier, and a pawl movably mounted thereon, means actuated by or through a change in the condition of the filling to move 75 the pawl-carrier into inoperative position, and separate means operated by or through warp failure to move the pawl relatively to the pawl-carrier, to render the pawl inoperative.

2. In a loom, take-up mechanism, let-back 80 means, means to arrest take-up and permit operation of the let-back means by or through a change in the condition of the filling, and separate means to arrest take-up by or through warp failure. 85

3. In a loom, take-up mechanism, let-back means, a shipper, means to release the shipper and arrest take-up simultaneously, and means operative by or through a change in 90 the condition of the filling to arrest take-up and effect the operation of the let-back means.

4. In a filling-replenishing loom, take-up mechanism, let-back means therefor, means to arrest take-up and permit operation of the let-back means upon filling replenishing, and 95 separate means to arrest take-up by or through warp failure, the let-back means remaining inoperative.

5. In a loom provided with filling-replenishing mechanism, take-up mechanism, let-back 100 means therefor, a shipper, means to release the shipper and arrest take-up simultaneously, and means to arrest the take-up and effect the operation of the let-back means upon filling replenishment. 105

6. In a loom, take-up mechanism, including a pawl-carrier, an actuating-pawl pivotally mounted thereon, and detent and let-back pawls, means operated by or through a change in the condition of the filling to move the pawl-carrier to disengage the actuating and detent pawls from the ratchet and permit let-back thereof, and separate means operated by or through the occurrence of a warp fault to move the pawl relatively to the pawl-carrier 110 and disengage it from the ratchet, the detent-pawl remaining in co-operative engagement therewith. 115

7. In a loom, a shipper, take-up mechanism, including a pawl-carrier, and a pawl movably 120 mounted thereon, means actuated by or through a change in the condition of the filling to move the pawl-carrier into inoperative position, and means operating simultaneously with the release of the shipper to move the 125 pawl relatively to the pawl-carrier and thereby arrest take-up.

8. In a loom, a shipper, take-up mechanism, including a pawl-carrier, and a take-up-actuating pawl movably mounted thereon, means 130 actuated by or through a change in the condition of the filling to move the pawl-carrier

and thereby render said pawl inoperative, and means to move the pawl relatively to the pawl-carrier upon release of the shipper and to return the pawl to operative position by or
5 through return of the shipper to running position.

In testimony whereof I have signed my

name to this specification in the presence of two subscribing witnesses.

JONAS NORTHROP.
